Inventor:

George W. B. Evans

UNITED STATES PATENT OFFICE.

GEORGE W. B. EVANS, OF WILDERNESS, VIRGINIA, ASSIGNOR TO EVANS ORE REDUCTION COMPANY, OF WASHINGTON, DISTRICT OF COLUMBIA.

FURNACE FOR TREATING REFRACTORY ORES CONTAINING PRECIOUS METALS.

Application filed August 13, 1926. Serial No. 128,988.

My invention consists of a furnace for treating refractory ores containing precious metals.

The object of my invention is to produce a machine or furnace which treats the ores more perfectly than has ever been done heretofore and at the same time recover more values than has been done by any method previous to my invention, a fact established 10 by an experimental plant now in operation.

A further object of my invention is to produce a furnace which recovers the values in an economical manner and does not allow the metals to escape when the same become 15 volatile, as has been the case in other processes and machines or furnaces for treating such ores.

Reference is made to the accompanying drawings which form a part of these specifications, in which; Figure 1 is a sectional elevation of my invention, Figure 2 is a detailed view showing a cover plate for the opening through which ore is inserted into the inner revolving cylinder, and Figure 3 25 is a detailed view showing one manner of supporting the revolving cylinder on the drive shaft and the means for conveying hydrogen gas into said revolving cylinder.

Like characters of reference designate 30 corresponding parts in the several figures of the drawing.

My furnace consists of a cylindrical chamber 1 with an opening 2 closed by a cover 3, said cover being substantially airtight when 35 closed, the opening 2 allowing access to the inside of the cylindrical chamber 1. The cylinder 1 is supported by ends 4 and 4^a shown as heavy castings on the drawing, but other forms of ends may be used without departing from the spirit of my invention.

The ends 4 and 4^a support bearings 5 and 6 respectively for a horizontal shaft 7 which passes through the furnace and is driven by a pulley or sprocket wheel secured to the end 5 of shaft 7 from any suitable power.

Stuffing boxes 13 are arranged around the shaft 7 in the ends 4 and 4^a to prevent the escape of gases hereinafter mentioned from the cylinder 1. Surrounding the cylinder 1 0 is a combustion chamber 15 and a firebox 16 beneath the cylinder which forms a part of the combustion chamber. A stack is arranged at the top and to the rear of the furnace to allow of the escape of the particles

of combustion. Surrounding said firebox is 55 a wall composed of non-heat conducting material, such as firebrick or the like 18, to retain as much of the heat within the furnace as is possible.

A supply pipe 19 is carried through the 60 outer wall of the furnace where it connects with a pair of heating coils 20 and 21 arranged directly over the fire, for heating and superheating the gas which is to be conducted from said coils through a suitable 65 pipe-line 22, provided with a control valve 23 into the cylindrical chamber 1, and into a revolving cylindrical chamber within said chamber 1 hereinafter mentioned.

The cylindrical chamber 1 is provided with 70 an opening 24 in the lower side of the forward end thereof, said opening being closed by a suitable door 25, secured by a locking bar 26 engaging a pair of wedged lugs 27. The door is provided with beveled edges to 75 fit against similar surfaces around the opening in order to insure a tight fit to prevent the escape of gas. An outlet pipe 28 leads from the cylinder 1 to condensers 29 shown diagrammatically in the drawings. The pipe 28 is provided with a release valve 30 to allow the escape of excessive gas or gases contained in the cylinder 1. The front end plate 4 of the furnace is provided with an opening closed by a suitable door 31 through 80 which fuel is fed to the firebox. A door 32 directly beneath the door 31 but secured to the foundation of the furnace is provided for the removal of ash from the pit beneath the firebox.

The entire furnace including the cylindrical chamber 1, the end plates 4 and 4^a and the surrounding wall 18, is held together by a plurality of tie-rods 33 having nuts 34 at the ends thereof and bearing against the 85 outer surfaces of the end plates 4 and 4^a. The outer wall of the furnace is supported and reinforced by a plurality of T irons, and the furnace is mounted upon a masonry or concrete foundation 42 as shown.

The construction above described and shown is substantially the same as a companion case filed by me and bearing an even filing date with this application.

This application differs from the companion application in that the lifters described in said companion application are dispensed with and the following construction em-

bodied in lieu thereof, although the operation and the results obtained are the same in both applications,

Mounted within the cylinder 1 and free to rotate therein is a cylinder 50 secured to the shaft 7 by arms 51 of spiders 52 mounted upon said shaft. The cylinder 50 is provided with an opening 53 through which ore may be fed into said cylinder by placing a funnel 10 or chute down through the opening 2 leading to the cylinder 1. The opening 53 has a cover 54 secured by latch bolts 55 which may be easily operated by a socket wrench extended down through the opening 2. An eyelet 15 56 is secured to the cover 54 for the purpose of quickly removing said cover when desirous of filling the cylinder 50 with a charge of ore to be treated.

An opening 57 is provided in one end of 20 the cylinder 50 in order that it may be brought opposite the opening 24 for the purpose of removing the charge of ore within the cylinder 50 after the same has been treated. The opening 57 is closed by a cover which is secured in a manner similar to that for locking the cover 54 in place.

It is not necessary nor intended that the cylinder 50 be air and gas tight as is the cylindrical chamber 1, but the openings leading 30 into said chamber must be securely closed in order that ore will not spill out and interfere with the rotation of said inner cylinder 50. Arranged within the cylindrical chamber 50 are a series of lifting plates 58 extending the entire length thereof and secured at their ends to the inner walls of the end plates of said cylindrical chamber. The plates 58 are provided with upturned inner edges 59 which act in the same capacity for 40 holding the ore being lifted as do the upturned flanges of the lifters in my companion application.

While I have shown a spider form of construction for securing the cylinder 50 and its 45 lifting plates to the shaft 7 I may use some other method of securing the cylinder 50 to the shaft 7 as well as any necessary means for properly strengthening the cylinder and its plates without departing from the spirit 50 of my invention.

Hydrogen gas heated and superheated by the system of coils, or return pipes 20 and 21 is fed under pressure into the cylindrical chamber 50 by the pipe 22 which is controlled by a valve 23 as shown on the drawing. The pipe 22 is brought through the outer end wall 41 of the furnace adjacent to the shaft 7. The rear end wall 60 of the cylinder 50 is provided with an opening 61 55 surrounding the shaft 7 to accommodate the pipe 22 as it projects within the cylinder 50. A baffle plate 62 is provided around the shaft 7 in order to disperse the hydrogen gas as it comes from the pipe 22. The baffle plate 62 performs an additional function of

70 preventing the ore which is being treated within said cylinder from clogging up the end of the pipe 22.

The operation of my invention is as follows:

Pulverized refractory ore is mixed with certain chemicals mentioned in a process application filed even date herewith, by myself, is introduced into the inner revolving cylinder 50 through the openings 2 and 53, 75 after which said openings are closed by the covers 3 and 54 respectively. Intense heat is applied to the outer surfaces of the cylinder 1, said heat radiating to and into the inner cylinder 50. As soon as the heat has arisen 80 to a sufficiently high temperature the valve 53 is opened and hydrogen gas forced into the inner cylinder. The cylinder is revolved about its axis, at which time the plates 58 start the operation of lifting the ore contained therein, and each plate allows the ore to slide off gradually in the form of spray as said plate approaches the upper side of the cylinder. All of the ore will not drop off or leave the plates until they have passed 85 beyond the vertical plane through the cylinder at the top. In continuing their journey in the revolution each plate will again gather up ore which has fallen to the bottom and lift or carry it to the top as before. This gives 90 me a continuous flow of the ore through the gases contained within the cylinder.

95 The chemicals above mentioned due to the intense heat surrounding the cylinder 1 are converted into gases which, together with the hydrogen gas introduced through the pipe 22, thoroughly impregnate every particle of the ore as it is falling off the lifting plates, and after a predetermined time separate the precious metals from the baser 100 metals of the ore. Some metals, as has been found by experiment, become volatile, and these metals pass off through the opening 61 to the cylindrical chamber 1 and from thence to the condenser or condensers 29 where they 105 may be recovered.

Having thus described my invention, what I claim is:

1. In a stationary furnace designed for the purpose of treating refractory ores containing precious metals, an airtight chamber, means for admitting hydrogen gas into said chamber, an inner rotating cylindrical chamber, means for admitting hydrogen gas into said inner chamber, means for admitting ore into said inner rotating chamber, and means for extracting the treated ore from said chamber, substantially as shown.

115 2. In a stationary furnace designed for the purpose of treating refractory ores containing precious metals, a cylindrical airtight chamber, an inner rotating chamber, means for admitting hydrogen gas into said inner rotating chamber, means for admitting ore into said inner chamber, means for lifting 120

125

130

said ore, and dropping the same in the form of spray, means for relieving excessive gas pressure in the stationary chamber, and means for extracting the treated ore from the inner rotating chamber substantially as shown.

3. A stationary furnace designed for the purpose of treating refractory ores containing precious metals, a fixed airtight chamber, an inner rotating receptacle, and means for applying heat externally to the fixed chamber substantially as shown.

4. In a stationary furnace designed for the purpose of treating refractory ores contain-

ing precious metals, a fixed horizontal cylindrical chamber, an inner rotating cylindrical receptacle, means for admitting hydrogen gas into said inner receptacle, means for inserting ore into said inner receptacle, means for lifting and dropping said ore in the form of spray within said inner receptacle, means for supplying heat externally to the fixed cylinder, and means for extracting the ore from the inner receptacle substantially as shown.

In testimony whereof I hereby affix my signature.

GEORGE W. B. EVANS.
